Application June 20, 1936, Serial No. 63,416

Term of patent 14 years

To whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in a plain ground fabric and series of alternating fine and heavier warp threads, the warp threads containing a multiplicity of irregularly twisted slubs having seed-like nubs disposed thereon.

I claim:

The ornamental design for a textile fabric or similar article of manufacture substantially as shown and described.
